UNITED STATES PATENT OFFICE.

EDWIN A. ORMSBY, OF MELROSE, MASSACHUSETTS.

WINDOW.

Application filed May 12, 1925. Serial No. 29,361.

This invention relates to a window comprising a frame and lower and upper sashes slidable vertically in the frame between guides on the upright members of the frame, 5 said guides performing the functions of the usual stop beads and parting beads of an ordinary window of this type.

The chief object of the invention is to provide a window, the sashes of which are provided with counterbalancing mechanisms, causing them to remain in various positions to which they are movable, and are adapted to be swung into the room with the counterbalancing mechanisms, so that the glass may 15 be conveniently washed by a person within the room, and the sashes and the counterbalancing mechanism may be rendered operative by the operation of restoring the sashes to a vertical position.

20 I attain this and other related objects by the improvements hereinafter described and claimed.

Of the accompanying drawings forming a part of this specification,

25 Figure 1 is a perspective view of a window embodying the invention, both sashes being upright.

Figure 2 is a view similar to Figure 1, showing the lower sash swung inward.

30 Figure 3 is a section on line 3—3 of Figure 1.

Figure 4 is a side view looking toward the outer side of the lower sash, and showing the swinging sections of the inner guides 35 hereinafter described.

40 Figure 4^a is a fragmentary sectional view, showing portions of the shaft hereinafter described, and its gears, portions of a sash, and portions of a torsion spring engaged with the shaft and sash.

Figure 5 is an edge view, showing the lower sash and one of the swinging sections shown by Figure 4.

45 Figure 6 is a section on line 6—6 of Figure 2.

Figure 7 is a section on line 7—7 of Figure 1.

Figure 8 is a section on line 8—8 of Figure 1.

50 Figure 9 is a perspective view of one of the detent members shown by Figure 8.

Figure 10 is a section on line 10—10 of Figure 4.

55 Figure 11 is an edge view of the window, showing the frame partly in section and both sashes swung inward.

Figure 12 is a fragmentary view, showing parts of the frame and of the lower portions of the outer sash guides.

Figure 13 is a section on line 13—13 of 60 Figure 12, looking toward the left.

Figures 14 and 15 are fragmentary views, showing the upper portions of the outer sash guides.

Figure 16 is a section on line 16—16 of 65 Figure 14.

Figure 17 is a section on line 17—17 of Figure 14.

The same reference characters indicate the 70 same parts in all of the figures.

The frame of a window embodying my invention may be of any suitable construction and material. The upright members 20 of the frame are provided with inner and outer sectional guides for the lower sash 21 75 and the upper sash 22. The inner guides perform the function of the usual stop beads which guide the lower sash, and each is composed of an upper section 23, fixed to the frame, and a lower swinging section 24, 80 hinged at its lower end to the frame, preferably by a pin or screw 25 (Figure 3). The swinging sections are adapted to swing inward from the frame, as shown by Figure 2. When the swinging sections 24 are upright, 85 their upper ends, which are preferably bevelled, abut against the bevelled lower ends of the fixed sections 23, so that the sections are in alinement with each other and constitute continuous guides.

90 The swinging sections are releasably secured to the frame by detents which may be of any suitable construction. One of the detents is shown by Figure 8, as composed of a slotted plate 26 (Figure 8), inserted in a recess in the inner face of the frame, and a key composed of a shank 27 (Figure 9), having a hook 28 and a head 29 adapted to turn in a recess in the inner face of the swinging guide section 24. The hook 100 is passed through the slot in the plate 26, and the shank is then turned to cause the hook to bear on the inner side of the plate, so that the swinging section is locked to the fixed section.

105 A counterbalancing mechanism is carried by the swinging sections 24 and the sash 21, and is adapted to maintain the sash at different positions to which it is movable on the guides. Said mechanism includes racks 31, fixed to the swinging sections 24, a shaft 32 journaled in bearings 33

(Figure 4^a) at opposite ends of a cavity 34 in the bottom rail of the sash, gears 35 fixed to the shaft and meshing with the racks, and a torsion spring 36, fixed at 37 to the shaft, 5 and at 38 to the sash, or to one of the bearings 33, and maintained at a suitable tension, to act through the gears and racks in preventing movement of the sash by gravity, when the sash is upright, the tension of the 10 spring being such that rotation of the shaft and gears is permitted when the sash is forcibly moved up and down.

I prefer to make the torsion spring in two independent parts or sections, each fixed at 15 one end to the shaft, and at the other end to the sash, so that in the event of breakage of one part, the other will continue operative.

The swinging sections 24 are longer than 20 the sash as shown by Figures 1, 2, 4, 5 and 7, so that said sections, the sash, and the counterbalancing mechanism may be displaced or swung inward as a unit, as shown by Figure 2, to permit the washing of the glass, 25 the operativeness of the counterbalancing mechanism being unaffected by this displacement. The combined length of the guide sections 23 and 24 is such that when the sections are in alinement with each other, the 30 sash 21 may be raised to the top of the frame.

The upright sides of the sash 21 are provided with plates 40 (Figures 4, 5 and 10) having ears 41 (Figure 10) confining the 35 sash in sliding contact with the racks 31, the swinging sections 24 being provided with grooves 42, into which the ears 41 project. Provision is thus made for so engaging the 40 swinging sections with the sash as to prevent independent swinging movement of either section, the sash and its plates 40 constituting a connection between the two 45 swinging sections.

The sash may be locked against endwise 45 movement on the swinging sections by the engagement of a locking dog 43 (Figures 5 and 10) with teeth of one of the gears 35. Said dog is slideable in a groove 44, in an upright stile, and may be manipulated when 50 the sash is swung inward to engage a gear, and thus prevent rotation of the gears and sliding movement of the sash.

I preferably provide restraining means, 55 adapted to support the swinging end of the sash when it is swung inward, and thus support the sash in a desirable position for washing. Said restraining means includes pulleys 46 (Figure 6) journaled on fixed studs 47 in recesses in the frame, springs 48, 60 fixed at 49 to the studs, and at 50 to the pulleys, and tethers 51, fixed to the pulleys and the sections 24. The springs are adapted to rotate the pulleys in the direction required to wind the tethers, so that when the 65 sash is upright, the tethers are taken up by

the pulleys. When the sash is inclined inward the tethers are unwound, and the springs are tensioned so that the tethers support the swinging end of the sash against downward movement from any inwardly 70 swung position in which it may be left. The tethers may be lengths of wire cord.

The upper sash 22 is slideable between inner guides performing the function of the usual parting beads, and the outside stop 75 beads 53 (Figure 2) with which the upright members of the frame are provided. Said inner guides are shown by Figures 11 to 17, 80 and each includes a fixed upper section 54 (Figures 11, 14 and 15), a fixed lower section 55, and a swinging intermediate section 56. The swinging intermediate sections 56 are connected by hinges 58, with the fixed lower sections 55, the swinging sections 85 being adapted to swing inward, as shown by Figure 11, and by dotted lines in Figure 12.

When the swinging sections 56 are upright, their upper ends, which are preferably bevelled, abut against the lower ends of the 90 fixed upper sections 54, all the sections being in alinement with each other and constituting continuous guides.

The swinging sections 56 are releasably secured to the fixed upper sections 54 by 95 detents, including bolts 59 (Figures 14 and 15) slideable in vertical guides 60 in the upper sections, and sockets 61 in the swinging sections, adapted to receive said bolts, the latter being movable by handles 62 projecting through slots 63 in the upper sections. 100

A counterbalancing mechanism is carried by the swinging sections 56 and the upper sash 22, and is adapted to maintain the sash at different positions to which it is movable. Said mechanism is in all essential particulars like that above described in connection with the lower sash 21 and the swinging sections 24, and includes racks 64, fixed to the swinging sections 56, a shaft 65 (Figure 110 11) journaled in bearings in a cavity in the bottom rail of the upper sash, gears 66 fixed to the shaft and meshing with the racks, and a torsion spring 67, shown by dotted lines in Figure 12, fixed to the shaft and to the 115 sash, and operating like the spring 36 already described.

The swinging sections 56 are longer than the upper sash, as shown by Figure 11, so that said sections, the sash, and the counterbalancing mechanism may be swung inward as a unit, after the inward swinging of the lower sash. The combined length of the sections 54, 55 and 56 is such that when the sections are in alinement with each other, the upper sash may be lowered to the bottom 125 of the frame.

To ensure the operativeness of the counterbalancing mechanism when the upper sash is completely lowered, I provide the 130

fixed lower sections 55 with racks 64^a constituting extensions of the racks 64, as shown by Figures 12 and 13, and meshing with the gears 66, when the bottom rail of the 5 upper sash is below the hinges 58, connecting the lower and swinging sections.

The swinging end of the upper sash may be restrained by means similar to the means described in connection with the lower sash, 10 and including tethers 51^a, connected with spring pulleys 46^a on the frame and with the sections 56.

The arrangement is such that when the lower sash and the swinging sections 24 are 15 displaced inward, the upper sash and the swinging sections 56 are free to be similarly displaced, the sections 56 being adapted to swing under the fixed upper sections 23. The upper sash may be moved to project inwardly from the sections 56, as shown by Figure 11, to facilitate washing.

I claim:

1. A window comprising a frame, upper and lower sash adapted to be adjusted vertically in said frame, sectional guides on the frame for the lower sash, each guide including a fixed upper section and a swinging lower section, means for releasably securing the swinging sections of said guides in alignment with the fixed sections thereof, the lower sash being connected with the swinging guide sections to swing therewith relative to the window frame and adapted to move relative to the guides in any position, and connections between the lower sash and the window frame for automatically checking swinging movement of said sash and retaining it in any desired inclined position.

2. A window comprising a frame, sectional sash guides on the upright members of the frame, each guide including a fixed upper section and a swinging section, means

for releasably securing the swinging sections of the guides in alignment with the fixed sections thereof, a sash connected to 45 the swinging sections of each of said guides by means whereby the sash will swing with said guide sections and is movable longitudinally of the guide sections in any adjusted position, and means for automatically 50 checking the swinging movement of either sash and retaining it at any desired inclination to the window frame.

3. A window comprising a frame having sash guides composed of fixed sections and pivoted sections adapted to be moved to and from alignment with the fixed sections, means for releasably securing the pivoted sections in alignment with the fixed sections, a sash slidable vertically of the guides, when 60 the sections thereof are aligned, and connected to the pivoted guide sections to be supported thereby and slide thereon when said pivoted sections are disconnected from the fixed sections, and a counter-balance 65 mechanism supported wholly by the sash and the pivoted guide sections, whereby said pivoted guide sections, the sash and the counter-balance mechanism may be swung inwardly, as a unit, from the frame to permit 70 access to both sides of the sash from within a room, and outwardly, as a unit, to restore the sash to a vertical position, the counter-balance mechanism presenting no limitation 75 to the extent of inward swinging movement of the pivoted guide sections and sash.

4. A window as specified in claim 3 having means for automatically checking the inward swinging movement of the sash and counterbalance mechanism, and retaining 80 said parts in any desired angular position.

In testimony whereof I have affixed my signature.

EDWIN A. ORMSBY.
